US00D624051S

(12) **United States Design Patent**
Shimizu et al.

(10) **Patent No.:** **US D624,051 S**
(45) **Date of Patent:** ** *Sep. 21, 2010

(54) **ADAPTER**

(75) Inventors: **Yosuke Shimizu**, Tokyo (JP); **Masaaki Ohara**, Tokyo (JP)

(73) Assignee: **Sony Corporation**, Tokyo (JP)

(**) Term: **14 Years**

(21) Appl. No.: **29/347,139**

(22) Filed: **Sep. 30, 2009**

(30) **Foreign Application Priority Data**

(57) **CLAIM**

The ornamental design for an adaptor, as shown and described.

DESCRIPTION

FIG. 1 is a front right top perspective view of an adaptor showing our new design;

FIG. 2 is a rear left top perspective view thereof;

FIG. 3 is a front left bottom perspective view thereof;

FIG. 4 is a rear right bottom perspective view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof; and,

FIG. 10 is a bottom plan view thereof.

Portions in broken lines are for illustrative purpose only and form no part of the claimed design. The dot-dash broken lines define but are not included in, the boundaries of the claimed design.

1 Claim, 10 Drawing Sheets
